UNITED STATES PATENT OFFICE.

THOMAS E. CARPENTER, OF PROVIDENCE, RHODE ISLAND.

NOSE-GRIP FOR EYEGLASSES.

No. 922,853.

Specification of Letters Patent.

Patented May 25, 1909.

Application filed October 3, 1908. Serial No. 455,947.

To all whom it may concern:

Be it known that I, THOMAS E. CARPENTER, a citizen of the United States, residing at Providence, in the county of Providence and State of Rhode Island, have invented 5 certain new and useful Improvements in Nose-Grips for Eyeglasses, of which the following is a specification, reference being had therein to the accompanying drawings.

Like reference characters indicate like 10 parts.

Figure 1 is a front elevation of a pair of eye-glasses provided with my improved nose grip. Fig. 2 is side elevation of said 15 nose grip. Fig. 3 is a view of said nose grip as seen in elevation. Fig. 4 is the same as Fig. 3, except that the nose grip is shown as mounted upon the end of the bridge, the latter being represented as seen in cross section 20 upon the line $z z$ of Fig. 5. Fig. 5 is a top plan view of the end of the bridge and lens-clamp. Fig. 6 is a front elevation of the same. Fig. 7 is a cross sectional view on line $y y$ of Fig. 6. Fig. 8 is a top plan view 25 of the end of the bridge and of the lens-clamp with my improved nose grip mounted thereon. Fig. 9 is a cross sectional view of the nose-pad as seen on line $x x$ of Fig. 8.

My invention is a nose grip for eye-glasses, 30 and relates particularly to the class of finger-operated nose grips.

It consists of the novel construction and combination of the several parts thereof as herein after described and as specifically set 35 forth in the claims.

In Fig. 1 the reference numeral 1 represents the lenses of a pair of eye-glasses and 2 is the bridge connecting said lenses. Each 40 end of the bridge adjacent to the lenses, respectively, comprises three parts,—a stud or disk-like body 3, two lens-supporting prongs 4 and two parallel ear pieces 5, commonly called the straps. The straps 5 have two oppositely located holes 6 and 7, in alinement 45 with each other, the hole 6 being provided with a screw-thread, and the hole 7 being countersunk for the reception of the head of a screw. Each pair of straps 5 receives between them the edge of a lens 1, and a screw 50 8 passes through a hole in the lens 1 made therefor, the threads of said screw engaging with the threaded hole 6 of one of said straps, and the head of the screw being seated in the countersunk hole 7 of the other of said straps.

In the edge of the stud 3 there are the

notch 9 and socket 10, the notch 9 opening into the socket 10, but of smaller dimensions. This combination of the notch 9 and socket 10, results in the formation of a lip, as plainly seen in Fig. 4, extending parallel to the upper 60 and lower plane surfaces of the stud. The stud also has in its lower side the small round hole 11, which is located out of vertical alinement with the notch 9 and socket 10.

The nose grip is designated as 12. On its 65 outer end the nose grip has a tubular piece 13 loosely mounted and held from longitudinal displacement by the headed end 14 of the said grip. The tube 13 is therefore capable of a swiveling action on the nose grip 12, the 70 latter being at and near its end cylindrical in shape. A nose-pad 15 is located diagonally upon the tube 13 and is fastened by solder or otherwise. The bearing surface of the pad 15 is preferably corrugated longitudinally, as 75 seen at 16, or otherwise roughened in order that it may have the requisite frictional contact with the nose.

The whole nose grip is made of tempered metal so as to have sufficient resiliency for 80 the spring - action hereinafter explained. With the exception of the end adjacent to the head 14, the nose grip is preferably made of flat stock.

The end of the nose grip opposite to the 85 head 14 is formed into the bow shape, illustrated at 17, and is also curved as shown at 18. The end of the bow 17 has the terminal bent pin 19, which extends into close proximity with the straight or central portion of 90 the nose grip and at a right angle thereto. An L-shaped hook 20, 21, extends from said straight portion of the nose grip 12, in the same plane with the pin 19, within the bow portion 17, the end of the pin 19 being in 95 close proximity with the end of the hook 21. The portion of the bow 17 adjacent to the pin 19 is bent slightly sidewise, as illustrated in Figs. 2 and 8; and whereas the notch 9 and socket 10 are directed radially inward, 100 as shown in Figs. 7 and 8, the hole 11 is located out of vertical alinement with the notch 9 and socket 10.

The parts are assembled as follows. The hook 20, 21, is inserted in the notch 9 and 105 socket 10, as represented in Figs. 4 and 7, and thus that portion 21 of said hook which is parallel to the straight portion of the nose grip 12 underlies the outer surface of the stud 3, as appears by the dotted line 110

in Fig. 5 adjacent to the curved edge of the notch 9 there shown. The pin 19 of the resilient arm or bow 17 is then brought to the under side of the stud 3 and is sprung into engagement with the hole 11, as most plainly seen in Fig. 4, the relative position of said pin being clearly exhibited in Figs. 7 and 8.

The bent end 21 of the hook, when engaged as in Fig. 4, prevents vertical displacement 10 of the nose grip and maintains it in the position there shown, though not in any manner interfering with the swiveling movement of the hook in the stud. The partial rotation of said hook is limited by the converging 15 walls of the socket 10 and the contact of the parts 20, 21 of the hook therewith. The engagement of the pin 19 in the hole 11 of the stud 3 prevents any lateral detachment of the nose grip 12 from the stud 3, though not 20 interfering with the proper swiveling movement of the nose grip.

The portion of the bows where marked 17 in Figs. 1, 3 and 4, being bent, as shown at 18, adapts them for use as finger-pieces. 25 The nose-pads are normally in the position shown in Figs. 1 and 8, having a spring-pressure inwardly against the two sides of the nose of the wearer, and at that time the two bows or finger-pieces 17 extend outwardly 30 toward the lenses 1, respectively.

To detach the eye-glasses from the nose, the two bows or finger pieces 17, are pinched slightly toward each other in an inward movement by the thumb and forefinger, and 35 consequently, as the hook 20, 21, swivels in the notch 9 and socket 10, the nose-pads 15 move apart out of contact with the nose and the eye-glasses are then removed from their wearing position.

40 The spring-action required for maintaining the proper frictional contact of the nose-pads 15 with the nose, is afforded by the end of the bow 17. When the finger-piece 17, is moved, as above described, in the direction indicated by the arrow 22 in Fig. 8, the straight portion 12 of the nose grip turns on the hook 20, 21, as a center, but as the end of the bow 17 is confined by the engagement of the pin 19 in the hole 11 of the stud 3 and 45 said hole is eccentric to the notch 9 and socket 10, said end of the bow 17 is put under tension, so that whenever the said finger manipulation ceases and the nose grip is free to act, it resumes automatically its normal 50 position shown in Fig. 8.

The swiveling action of the tubes 13 on the outer cylindrical portion of the nose grip 12 enables the nose-pads 15 to assume automatically such angular positions as to conform them to the shape of the nose. This 60 nose grip is easily detached from the stud 3, whenever desired, by first withdrawing the pin 19 from the hole 11 of said stud, and then withdrawing the hook 20, 21, from the 65 notch 9 and socket 10.

To vary the tension of the spring, the end of the bow 17, where the pin 19 is, can be slightly bent by, the thumb and forefinger, or by a suitable tool, either in the direction indicated by the arrow 23 in Fig. 2 to increase the tension, or in the opposite direction to lessen the tension.

I claim as a novel and useful invention and desire to secure by Letters Patent;—

1. The combination of a bridge; a stud at 75 the end of the bridge, having in one edge a socket and a notch opening thereinto and on the under side a hole out of line with the socket; and a resilient nose grip having a hook engageable with said socket and notch and a 80 bow whose end carries a pin engageable with the hole.

2. The combination of a bridge; a stud at each of the two ends of the bridge, having in 85 one edge a socket and a notch opening thereinto and on the under side a hole out of line with the socket; and a resilient nose grip on each of said studs having a hook engageable with said socket and a bow whose end carries 90 a pin engageable with said hole, the outward ends of said bows being bent in opposite directions to constitute them manually-operated finger-pieces.

3. The combination of a stud having a radially directed socket on one edge and on the 95 under side a hole out of line with the socket; a nose grip having a central hook engageable with said socket and a bow at one end provided with a terminal pin engageable with said hole; a tube loosely mounted on the opposite end of the nose grip and adapted to 100 swivel thereon; and a nose pad secured on the tube in an angular direction.

4. The combination of a bridge; a stud at the end of the bridge having in one edge a 105 socket with a projecting lip and on the under side a hole out of line with the socket; and a resilient nose grip mounted on the stud by a hook which extends into said socket beneath the projecting lip and provided with a terminal pin engageable with the hole.

5. The combination of a bridge; a stud at the end of the bridge having in one edge a socket and on its under side a hole out of line 115 with the socket; a resilient nose grip mounted on the stud by a hook which extends into said socket and also provided with an integral pin engaging pivotally in said hole, whereby the resilient arm when moved is put under tension by the eccentric position of 120 said pin with reference to said socket.

6. The combination of a bridge; a stud at the end of the bridge and having a socket in its edge; a nose grip made of tempered stock and movable on said stud; a hook on the nose 125 grip engageable with said stud in the socket thereof and adapted to allow movement of the nose grip in one plane; and means integral with the nose grip and adapted to prevent separation of the nose grip in said plane. 130

7. The combination of a bridge; a stud at the end of the bridge and having a socket in its edge; a nose grip movable on the stud; a hook on the nose grip engageable with the stud
5 in the socket thereof and adapted to allow movement of the nose grip on the stud in one plane; and resilient means on said nose grip comprising a pin and spring arm and capable of a spring engagement with the stud to se-
cure the nose grip against detachment there- 10 from.
- In testimony whereof I affix my signature in presence of two witnesses.
